UNITED STATES PATENT OFFICE.

JOHN S. BUSKY, SR., OF NEW YORK, N. Y.

SHOE-LAST.

1,078,251.

Specification of Letters Patent.

Patented Nov. 11, 1913.

Application filed April 1, 1912. Serial No. 687,664.

To all whom it may concern:

Be it known that I, JOHN S. BUSKY, Sr., a citizen of the United States, and a resident of New York, county and State of New York, have invented a certain new and useful Improvement in Shoe-Lasts, of which the following is a full, clear, and exact specification.

This invention relates to a class of devices 10 or shoe lasts adapted to be used in making footwear.

My invention has for its object primarily to provide a last or device designed to be employed for making shoes, boots, and other 15 forms of footwear for persons whereby the use of tacks or nails may be dispensed with as is incident with the making of footwear according to present methods, and which is adapted to be used to permit persons afflicted 20 with blindness to efficiently make various forms of footwear. These advantages are attained mainly by providing a hollow last, or shell of a suitable shape, and upon which the various parts of the shoe are fastened 25 together. By the use of shaping plates the "upper" or vamp of the shoe may be readily stretched in proper form upon the last, and held so that an insole and an outsole if desired may be stitched thereto either singly, 30 or collectively.

Other objects of the invention are to provide means adapted to operate the shaping or stretching plates for holding the "upper" or vamp; to provide means serving to adjust 35 the plates so as to form the "upper" in proper shape; and to provide means adapted to securely hold the insole to the last so as to be stitched to the "upper" or vamp.

A further object of the invention is to provide an efficient form of shoe last which is susceptible of being made in different forms, in order to be used for making footwear of 40 various shapes and sizes.

A practical embodiment of the invention 45 is represented in the accompanying drawing forming a part of this specification in which similar characters of reference indicate corresponding parts in all the views, the said invention being more fully described hereinafter and then pointed out in the appended claims.

In the drawing Figure 1 is an inverted 50 view of the last with the bottom plate removed therefrom. Fig. 2 is a longitudinal vertical section, partly in detail, taken centrally through the last, and Fig. 3 is a frag-

mentary plan of the bottom plate of the last. Fig. 4 is a plan of a portion of the supporting plate used in the device, and Fig. 5 is a fragmentary section taken on the line II—II 60 of Fig. 1 showing the form of the fingers serving to guide the movement of the stretching plates.

The device has a last or shell 10 having a foot portion or upper part 11 and an ankle 12 which are made in the form of a person's foot of any size or shape. The foot portion 11 and ankle 12 are preferably made of sheet metal so as to provide a hollow interior 13 thereto and upon the lower edge of said foot portion is a bottom plate 14 having a plurality of spaced slots or openings 15 formed therethrough adjacent to its peripheral edge. The edge of the plate 14 extends some distance beyond the foot portion 11, and said projecting edge is peripherally corrugated, or notched, as 16. Upon the top surface of the bottom plate 14, and interiorly of the foot portion 11 of the shell are movable 70 shaping or stretching plates 17, 18, 19, 20. The shaping plates 17 and 18 are of approximately the same length as the foot portion 11 of the shell, and are disposed at the opposed lengthwise edges of the interior of the shell. The shaping plate 19 is movably held 75 at the heel interiorly of the foot portion, and the shaping plate 20 is movably held at the toe interiorly of said foot portion. Each of the shaping plates carries a plurality of pins 21 which extend vertically from the underside thereof, and are disposed through the slots 15 of the bottom plate 14. In proximity to the ends of each of the stretching plates 17 and 18, and upon their opposed edges are lugs 22 and 23, each of which has 80 an upwardly projecting pin 24 and 24^a.

Serving to carry the mechanism for moving the stretching plates 17, 18, 19, 20 alternately in vertical and radial directions, is a supporting plate 25 provided adjacent to the 100 stretching plates, and said supporting plate is of a size to permit it to be freely moved in the shell 10. Through the supporting plate 25 and in proximity to one end thereof are two alined spaced openings 26 and 27, 105 and in proximity to the opposite end of said supporting plate are two similar spaced openings 28 and 29. Contiguous to one end of the stretching plate 17 and extending from its underside is a guide 26^a, and a 110 guide 27^a extends from a corresponding part of the underside of the stretching plate 18.

A guide 28^a extends from the underside of the stretching plate 17 in proximity to its opposite end, and a guide 29^a extends from a corresponding part of the stretching plate 18. All of the guides are preferably alike, each being formed of two spaced strips which are cut out of the respective stretching plates and then disposed at suitable angles from the plates so as to be passed through one of the corresponding openings of the supporting plate 25. By then bending the strips of each guide in opposite directions so as to be disposed in overlapping arrangement relatively to the opposed surface of the supporting plate 25 the stretching plates 17 and 18 when moved will be properly guided back and forth in lateral directions.

Fastened by bolts, or otherwise, approximately centrally of the supporting plate 25 is a block or boss 30 having a recess 31 therein, and upon the surface of said boss opposite to the recess 31 is a post 32. The post 32 extends in proximity to the opening in the top of the shell 10, and said opening is closed by a plate 33 through which is an opening 34. The free end of the post 32 is exteriorly threaded, and upon said threaded end is the interiorly threaded end of a rotatable cap 35 having a reduced portion, as 36, which is disposed through the opening 34 of the plate 33. By providing the reduced portion 36 an annular shoulder is formed upon the cap 35, and said shoulder abuts against the plate 33. The reduced portion 36 of the cap 35 extends some distance beyond the plate 33 exteriorly of the shell 10, and upon this extension is a finger nut 37 which is held rigidly to said reduced portion by a screw 38, or otherwise, so as to permit the cap to be revolved thereby. When the nut 37 is manually rotated from right to left the cap 35 will likewise be revolved, and the boss 30 will then be forced for moving the supporting plate 25 and the stretching plates 17, 18, 19, 20 toward the bottom plate 14 of the shell 10. The pins 21 of the stretching plates will thereby be moved through the spaced slots 15 of the bottom plate 14 so as to extend some distance therefrom.

Through the cap 35, the post 32 and the boss 30 is a continuous passage 39 which communicates with the recess 31 of the boss, and in said passage is a movable spindle 38 of an adjusting device 40 which serves as means to move the plates 17, 18, 19, 20 and the pins 21 thereof in a direction toward the center of the bottom plate 14 so as to stretch the "upper" or vamp of a shoe when arranged upon the shell 10 of the last.

The adjusting device 40 has a pinion 41 rigidly held upon the spindle 38, and is disposed in the recess 31 of the boss 30. In parallel arranged longitudinal slots, or passages 42 and 43 formed at the edges of the

body of the boss 30 are guided the racks, or toothed arms 44 and 45 of operating bars, or members 46 and 47. As shown in Fig. 1, the teeth of both the racks 44 and 45 are in mesh with the pinion 41 whereby the racks 44 and 45 are moved simultaneously in opposite directions longitudinally with respect to the length of the shell 10. The operating bar 46 extends into the toe of the shell 10, and the operating bar 47 extends in a direction toward the heel of the shell. Serving to support as well as guide the movement of the operating bar 46 is an apertured bracket 48 fastened to the supporting plate 25, and the end of said operating bar which is opposite to the rack 45 is connected by means of a pin 49 to the ears of a lug 50 provided upon the edge of the stretching plate 20 at the toe of the last. The end of the operating bar 47 which is opposite to the rack 44 is connected by a pin 51 to the ears of a lug 52 formed upon the stretching plate 19 at the heel of the last. By connecting the toe stretching plate 19 and the heel stretching plate 20 in this manner to the operating bars 46 and 47, respectively, it is obvious that said stretching plates will be moved in unison in a direction toward the center of the bottom plate of the last when the racks 44 and 45 are longitudinally moved in opposite directions by rotation of the pinion 41. For the purpose of also forcing the stretching plates 17 and 18 in a direction toward the center of the bottom plate of the last simultaneously with the movement of the plates 19 and 20, connected to the operating bar 46 at the toe of the last is a plate, or guiding member 52^a, and connected to the operating bar 47 at the heel of the last is a similar plate, or guiding member 53. The guiding plates 52 and 53 may be substantially the shape of a cross, or any other preferred form, and in each of said plates are two converging slots 54 and 55. Movably disposed in the slots 54 and 55 of each of the guiding plates are the pins 24 and 24^a of each pair of the lugs 22 and 23 so that when the operating bars 46 and 47 are directed longitudinally, as above described, and the guiding plates 52 and 53 are correspondingly moved the edges of the slotted portions of said plates will engage and force the pins 24 and 24^a along the slots whereby the stretching plates 17 and 18 will be moved in unison toward the center of the bottom plate of the last. To rotate the pinion 41 to operate the stretching plates 17, 18, 19, 20 the spindle 38 extends some distance beyond the cap 39, and upon the projecting end of said spindle is a bar, or hand-lever 56 by the use of which the spindle may be manually rotated.

In employing the last for making footwear for persons without the use of nails the "upper" or vamp is directed over the

ankle and foot portion of the last, and the vamp is held against displacement by fastening its edges upon the pins 21 of the plates 17, 18, 19, 20 after being forced to extend through the slots of the bottom plate of the shell. In order to then properly stretch the vamp in shape the plates 17, 18, 19, 20 are moved radially in a direction toward the center of the bottom plate of the last by rotating the spindle 38 through the operation of the adjusting device 40 by the hand-lever 56. In order to apply an insole not shown to the "upper" or vamp it is made of the same size as the bottom plate 15 of the shell 10 of the last. The insole is provided with slots similar to the bottom plate and has also two spaced openings midway therethrough for passage of bolts or pins 57 and 58 of a holding device 59. The bolts 57 and 58 are held rigidly in the bottom plate 14 of the shell 10, and each of said bolts has a threaded end projecting some distance from the bottom plate. A plate or bar 60 having two openings is 20 movably held upon the threaded ends of the bolts 57 and 58, and by means of thumb nuts 61 and 62 the plate is tightened upon an insole after being positioned upon the bottom plate of the shell, as heretofore mentioned. By using the corrugations 16 of the bottom plate 14 as guides the insole may 25 then be evenly stitched to the "upper" or vamp.

In the foregoing description I have embodied the preferred form of my invention, but I do not wish to be understood as limiting myself thereto, as I am aware that modifications may be made therein without departing from the principle, or sacrificing 30 any of the advantages of this invention, therefore I reserve to myself the right to make such changes as fairly fall within the scope thereof.

Having thus described my invention, I 45 claim as new and desire to secure by Letters Patent:—

1. The combination with a shoe last having a hollow foot portion, of a bottom plate provided upon the lower face of the foot portion and having a peripherally corrugated edge extending beyond the foot portion, said bottom plate having a plurality of spaced slots adjacent to its corrugated edge, a plurality of stretching plates movably held within the foot portion, a plurality of pins provided upon each of the stretching plates and adapted to be projected through the slots of the bottom plate, means adapted to force the stretching plates 50 simultaneously toward the bottom plate whereby the pins of said stretching plates will be projected through the slots of the bottom plate for fastening the vamp of a shoe upon the last, and means adapted to move the stretching plates 55 simultaneously toward the bottom plate whereby the pins of said stretching plates will be projected through the slots of the bottom plate for fastening the vamp of a shoe upon the last, and means adapted to move the stretching plates 60 simultaneously toward the bottom plate whereby the pins of said stretching plates will be projected through the slots of the bottom plate for fastening the vamp of a shoe upon the last, and means adapted to move the stretching plates 65 simultaneously toward the bottom plate whereby the pins of said stretching plates will be projected through the slots of the bottom plate for fastening the vamp of a shoe upon the last, and means adapted to move the stretching plates 70 simultaneously toward the bottom plate whereby the pins of said stretching plates will be projected through the slots of the bottom plate for fastening the vamp of a shoe upon the last, and means adapted to move the stretching plates 75 simultaneously toward the bottom plate whereby the pins of said stretching plates will be projected through the slots of the bottom plate for fastening the vamp of a shoe upon the last, and means adapted to move the stretching plates 80 simultaneously toward the bottom plate whereby the pins of said stretching plates will be projected through the slots of the bottom plate for fastening the vamp of a shoe upon the last, and means adapted to move the stretching plates 85 simultaneously toward the bottom plate whereby the pins of said stretching plates will be projected through the slots of the bottom plate for fastening the vamp of a shoe upon the last, and means adapted to move the stretching plates 90 simultaneously toward the bottom plate whereby the pins of said stretching plates will be projected through the slots of the bottom plate for fastening the vamp of a shoe upon the last, and means adapted to move the stretching plates 95 simultaneously toward the bottom plate whereby the pins of said stretching plates will be projected through the slots of the bottom plate for fastening the vamp of a shoe upon the last.
2. The combination with a shoe last having a hollow foot portion, of a bottom plate provided upon the lower face of the foot portion and having a peripherally corrugated edge extending beyond the foot portion, said bottom plate having a plurality of spaced slots adjacent to its corrugated edge, a plurality of stretching plates movably held within the foot portion, a plurality of pins provided upon each of the stretching plates and adapted to be projected through the slots of the bottom plate, a supporting plate movable within the foot portion, guides provided upon the stretching plates and co-operating with the supporting plate for guiding the stretching plates when moved, means adapted to force the supporting plate so as to move the stretching plates simultaneously toward the bottom plate whereby the pins of said stretching plates will be projected through the slots of the bottom plate for fastening the vamp of a shoe upon the last, and means adapted to move the stretching plates simultaneously in a direction toward the center of the bottom plate whereby the vamp of the shoe may be stretched upon the last.
3. The combination with a shoe last having a hollow foot portion and an opening through the top thereof, of a bottom plate upon the lower face of the foot portion having a peripherally corrugated edge extending beyond the foot portion and a plurality of spaced slots adjacent to its corrugated edge, a plurality of stretching plates movably held within the foot portion, a plurality of pins provided upon each of the stretching plates and adapted to be projected through the slots of the bottom plate, a supporting plate movable within the foot portion, guides provided upon the stretching plates and co-operating with the supporting plate for guiding the stretching plates when moved, means adapted to force the supporting plate so as to move the stretching plates simultaneously toward the bottom plate whereby the pins of said stretching plates will be projected through the slots of the bottom plate for fastening the vamp of a shoe upon the last, and means adapted to move the stretching plates simultaneously in a direction toward the center of the bottom plate whereby the vamp of the shoe may be stretched upon the last.
4. The combination with a shoe last having a hollow foot portion and an opening through the top thereof, of a bottom plate provided upon the lower face of the foot portion and having a peripherally corrugated edge extending beyond the foot portion, said bottom plate having a plurality of spaced slots adjacent to its corrugated edge, a plurality of stretching plates movably held within the foot portion, a plurality of pins provided upon each of the stretching plates and adapted to be projected through the slots of the bottom plate, a supporting plate movable within the foot portion, guides provided upon the stretching plates and co-operating with the supporting plate for guiding the stretching plates when moved, means adapted to force the supporting plate so as to move the stretching plates simultaneously toward the bottom plate whereby the pins of said stretching plates will be projected through the slots of the bottom plate for fastening the vamp of a shoe upon the last, and means adapted to move the stretching plates simultaneously in a direction toward the center of the bottom plate whereby the vamp may be stretched upon the last, and means adapted to rigidly hold an insole or the like upon the bottom plate so as to be stitched to the vamp.
5. The combination with a shoe last having a hollow foot portion and an opening through the top thereof, of a bottom plate provided upon the lower face of the foot portion and having a peripherally corrugated edge extending beyond the foot portion, said bottom plate having a plurality of spaced slots adjacent to its corrugated edge, a plurality of stretching plates movably held within the foot portion, a plurality of pins provided upon each of the stretching plates and adapted to be projected through the slots of the bottom plate, a supporting plate movable within the foot portion, guides provided upon the stretching plates and co-operating with the supporting plate for guiding the stretching plates when moved, means adapted to force the supporting plate so as to move the stretching plates simultaneously toward the bottom plate whereby the pins of said stretching plates will be projected through the slots of the bottom plate for fastening the vamp of a shoe upon the last, and means adapted to move the stretching plates simultaneously in a direction toward the center of the bottom plate whereby the vamp may be stretched upon the last, and means adapted to rigidly hold an insole or the like upon the bottom plate so as to be stitched to the vamp.

gated edge extending beyond the foot portion, said bottom plate having a plurality of spaced slots adjacent to its corrugated edge, a plurality of stretching plates movably held within the foot portion, a plurality of pins provided upon each of the stretching plates and adapted to be projected through the slots of the bottom plate, a supporting plate movable within the foot portion, guides provided upon the stretching plates and coöperating with the supporting plate for guiding the stretching plates when moved, a boss fastened upon the supporting plate, said boss having an exteriorly threaded portion extending toward the opening at the top of the last, an interiorly threaded cap rotatably held upon the threaded portion of the boss, and means adapted to rotate the cap to move the boss for forcing the supporting plate so as to move the stretching plates simultaneously toward the bottom plate whereby the pins of said stretching plates will be projected through the slots of the bottom plate for fastening the vamp of a shoe upon the last.

5. The combination with a shoe last having a hollow foot portion and an opening through the top thereof, of a bottom plate provided upon the lower face of the foot portion and having a peripherally corrugated edge extending beyond the foot portion, said bottom plate having a plurality of spaced slots adjacent to its corrugated edge, a plurality of stretching plates movably held within the foot portion, a plurality of pins provided upon each of the stretching plates and adapted to be projected through the slots of the bottom plate, a supporting plate movable within the foot portion, guides provided upon the stretching plates and coöperating with the supporting plate for guiding the stretching plates when moved, a boss fastened upon the supporting plate, said boss having an exteriorly threaded portion extending toward the opening at the top of the last, an interiorly threaded cap rotatably held upon the threaded portion of the boss and revoluble in the said top opening, means adapted to rotate the cap to move the stretching plates simultaneously toward the bottom plate whereby the pins of said stretching plates will be projected through the slots of the bottom plate for fastening the vamp of a shoe upon the last, and means adapted to move the stretching plates simultaneously in a direction toward the center of the bottom plate whereby the vamp may be stretched upon the last.

6. The combination with a shoe last having a hollow foot portion and an opening through the top thereof, of a bottom plate provided upon the lower face of the foot portion and having a peripherally corrugated edge extending beyond the foot por-

tion, said bottom plate having a plurality of spaced slots adjacent to its corrugated edge, a plurality of stretching plates movable held within the foot portion, a plurality of pins provided upon each of the stretching plates and adapted to be projected through the slots of the bottom plate, a supporting plate movable within the foot portion, guides provided upon the stretching plates and coöperating with the supporting plate for guiding the stretching plates when moved, a boss fastened upon the supporting plate, said boss having an exteriorly threaded portion extending toward said top opening, an interiorly threaded cap rotatably held upon the threaded portion of the boss and revoluble in the said top opening, means adapted to rotate the cap to move the stretching plates simultaneously toward the bottom plate whereby the pins of said stretching plates will be projected through the slots of the bottom plate for fastening the vamp of a shoe upon the last, means adapted to move the stretching plates simultaneously in a direction toward the center of the bottom plate whereby the vamp may be stretched upon the last, and means adapted to hold an insole or the like upon the bottom plate so as to be stitched to the vamp.

7. The combination with a shoe last having a hollow foot portion and an opening through the top thereof, of a bottom plate provided upon the lower face of the foot portion and having a peripherally corrugated edge extending beyond the foot portion, said bottom plate having a plurality of spaced slots adjacent to its corrugated edge, a plurality of stretching plates movably held within the foot portion, a plurality of pins provided upon each of the stretching plates and adapted to be projected through the slots of the bottom plate, means adapted to force the stretching plates simultaneously toward the bottom plate whereby the pins of the stretching plates will be projected through the slots of said bottom plate, a boss fastened within the foot portion and having an aperture therethrough and a recess therein, a spindle movable in the aperture of the boss, a pinion held upon the spindle and disposed in the recess of the boss, two operating bars, a rack formed upon one end of each of the operating bars and meshing with the pinion of the spindle, means connecting each of the operating bars to the stretching plates whereby the stretching plates may be moved toward the center of the bottom plate of the last when the operating bars are moved in opposite directions, and means adapted to rotate the spindle in the boss for revolving the pinion to move said operating bars.

8. The combination with a shoe last having a hollow foot portion and an opening

11. The combination with a shoe last having a hollow foot portion and an opening through the top thereof, of a bottom plate provided upon the lower face of the foot portion and having a peripherally corrugated edge extending beyond the foot portion, said bottom plate having a plurality of spaced slots adjacent to its corrugated edge, a plurality of stretching plates movably held within the foot portion, two of said plates being at 50 the opposed side edges and one each at the toe and heel of the foot portion, a plurality of pins provided upon each of the stretching plates and adapted to be projected through the slots of the bottom plate, a supporting 55 plate movable within the foot portion, guides provided upon the stretching plates and co-operating with the supporting plate for guiding the stretching plates when moved, a boss fastened upon the supporting plate and 60 having a recess therein, said boss having a passage therethrough, means carried by the boss and adapted to force the stretching plates simultaneously so as to project the pins thereof through the slots of the bottom 65 plate, a spindle movable in the passage of the boss, a pinion held upon the spindle and disposed in the recess of the boss, two operating bars, a rack formed upon one end of the operating bars to the stretching plates where- 70 of the spindle, means connecting each of the operating bars to the stretching plates whereby the stretching plates may be moved toward the center of the bottom plate 75 opposite directions, means adapted to rotate the spindle for revolving the pinion to move said operating bars, two threaded bolts rigidly held upon the bottom plate, a bar having two openings through which the threaded bolts are guided, and means adapted to move the bar to adjusted positions upon the threaded bolts.
12. The combination with a shoe last having a hollow foot portion and an opening through the top thereof, of a bottom plate provided upon the lower face of the foot portion and having a peripherally corrugated edge extending beyond the foot portion, said bottom plate having a plurality of spaced slots adjacent to its corrugated edge, four stretching plates movably held within the foot portion, two of said plates being at 50 the opposed side edges and one each at the toe and heel of the foot portion, a plurality of pins provided upon each of the stretching plates and adapted to be projected through the slots of the bottom plate, a supporting 55 plate movable within the foot portion, guides provided upon the stretching plates and co-operating with the supporting plate for guiding the stretching plates when moved, a boss fastened upon the supporting plate and 60 having a recess therein, said boss having a passage therethrough, means carried by the boss and adapted to force the stretching plates simultaneously so as to project the pins thereof through the slots of the bottom 65 plate, a spindle movable in the passage of the boss, a pinion held upon the spindle and disposed in the recess of the boss, two operating bars, a rack formed upon one end of the operating bars to the stretching plates where- 70 of the spindle, means connecting each of the operating bars to the stretching plates whereby the stretching plates may be moved toward the center of the bottom plate 75 opposite directions, means adapted to rotate the spindle for revolving the pinion to move said operating bars, two threaded bolts rigidly held upon the bottom plate, a bar having two openings through which the threaded bolts are guided, and means adapted to move the bar to adjusted positions upon the threaded bolts.

This specification signed and witnessed this thirtieth day of March A. D. 1912.
